UNITED STATES PATENT OFFICE.

HERMANN SCHRÖDER, OF NEW YORK, N. Y.

AIRSHIP.

1,120,981.

Specification of Letters Patent. Patented Dec. 15, 1914.

Application filed September 27, 1908. Serial No. 519,662.

To all whom it may concern:

Be it known that I, HERMANN SCHRÖDER, a subject of the Emperor of Germany, and a resident of New York city, county and State of New York, have invented certain new and useful Improvements in Airships, of which the following is a specification, reference being had to the accompanying drawings, forming a part thereof.

10 Air ships are sometimes divided roughly into two classes,—one known as the "heavier-than-air" in which the vessel is maintained in the air exclusively by means of mechanically operated devices, and the other known as the "lighter-than-air" type in which the vessel is caused to rise and maintain in the air from its own buoyancy, due to the fact that it displaces a quantity of air greater in weight than its own entire weight.

20 My present invention relates to a form of air ship which is in effect a combination of the two, in that it depends partly upon its own buoyancy, and partly upon mechanically operated devices, for lifting it and maintaining it in the air. In general, the air ship includes a rigid body inclosing a large air or gas space, and propelling mechanism including vertically arranged propelling means for inducing vertical air currents which tend directly to lift the machine, and also horizontal propelling means which produce horizontal currents for longitudinal propulsive purposes and which may also be 30 employed in combination with tilting horizontal rudders for raising and lowering the vessel while it is being propelled.

35 My invention consists in many novel features in addition to the means by which the vessel is raised and maintained in the air, including a peculiar form, construction, and arrangement of the propellers, the combination with the propellers of a conical chamber inclosing them, a novel form of 40 steering mechanism, comprising horizontally arranged laterally disposed propelling means, a novel arrangement of auxiliary sails, the provision of means for recharging the body with buoyant gas, and many 45 other novel details of construction and combinations of parts, such as will be fully pointed out hereinafter.

50 In order that my invention may be thoroughly understood, I will now proceed to 55 describe an embodiment thereof, having reference to the accompanying drawings illus-

trating the same, and will then point out the novel features in claims.

In the drawings: Figure 1 is a view in side elevation of an air ship embodying my invention. Fig. 2 is a view in central longitudinal section through the lower part of the central portion thereof, showing particularly the propelling mechanism. Fig. 3 is a top view of the air ship, with a portion 60 of the main body shown in cross section. Fig. 4 is an underside view upon a reduced scale. Fig. 5 is a detail view of the lateral steering propellers. Fig. 6 is a transverse sectional view through the air ship. Fig. 7 is a detail top view showing the drive and clutch connection between one of the motors and the driven shaft.

The main body 10 of the air ship is preferably a rigid structure comprising a framework 11 which may conveniently be composed of angle or T irons, and a metallic shell 12 which may be composed of thin nickel steel plates or other material of the required lightness and strength. The framework and the shell are intended to be so formed, constructed and secured together, and so braced as to be rigid throughout, and a plurality of transverse bulk heads 13 are provided both for the purpose of transversely bracing the structure and for the purpose of dividing the body, as a whole, into a plurality of compartments. The general form of the body in cross section is somewhat in the nature of an ellipse, except that the upper and lower walls preferably join each other angularly on medial lines. In the construction shown in the drawings the upper and lower walls are formed on the arcs of two circles whose centers are exterior (see particularly Fig. 6) of the space inclosed thereby. This general form is advantageous because of the fact that it offers a proportionately small lateral resistance to the wind, such resistance being very much smaller than if the body were cylindrical, as is quite common in this type of air ship.

The two compartments 14 and 15 at each end of the body, viewing the same longitudinally may be conveniently employed to carry water and a liquid fuel, such as gasoline, the same being properly piped to the motor or motors. The remaining compartments 16 are arranged to contain a gas lighter than air, as is common in dirigible balloons, and for the purpose of addition-

ally providing against leakage of this gas the said compartments may be lined throughout with oiled silk or other gas retaining substance 17. If preferred, the said 5 chambers may contain air or a gas lighter than air under a pressure less than atmospheric pressure, the latter being possible owing to the fact that the body is formed as a rigid structure. In the latter event it will, 10 of course, be necessary that the entire structure be air-tight, while in the former event the metallic structure need not be air or gas tight because of the linings 17 employed. In order to take care of any possible leakage 15 through the lining 17, and hence escape of gas therethrough, I have provided retorts 18 by which gas may be manufactured while the air ship is out of communication with the ground to supply gas to the various 20 compartments to take the place of that lost, whereby the lifting capacity of the body portion of the air ship may be kept substantially uniform.

It is not intended in the present instance 25 that the body portion should have a lifting capacity equal to the entire weight of the vessel, but that a portion of the lifting force shall be supplied by mechanism carried by the air ship. This mechanism comprises, 30 first, a plurality of propellers mounted upon vertically disposed shafts whose action will be to induce air currents directly downward whereby to exert a direct lifting force to the vessel, and second, in a plurality of propellers 35 arranged upon a horizontal shaft in combination with horizontal deflecting rudders by which a forward and upward movement may be imparted to the vessel. In the present instance I have shown a 40 group of six vertically arranged propelling elements 19 all connected together by suitable belts 20 with the main drive shaft 21 of the machine. The horizontal driving means comprise two groups of propellers 45 22—23 arranged at opposite ends of a horizontal shaft 24, the said shaft being connected with the main shaft 21 by means of gearing 25. The gearing 25 is controlled by means of clutch mechanism 26 and an 50 operating lever 27 by which the drive may be imparted in either direction, so that by the mere manipulation of the lever 27 the vessel may be propelled forward or backward at will. Two pairs of horizontal 55 rudders 28 are provided, the same being centrally pivoted at about the medial line of the body of the vessel, and the same are connected by means of suitable gearing 29 with a steering wheel 30 by which all of 60 them may be moved synchronously about their central horizontal pivots. By this means the forward ends of the rudders may be raised whereby the horizontal propelling mechanism, in driving the vessel forward, 65 will tend to lift the same along a gradual

incline, as will be well understood. Similarly the vessel may be depressed by lowering the front ends of the horizontal rudders.

For the purpose of steering the vessel laterally I have provided the usual rearwardly extending rudder 31 which is controlled through suitable gearing 32 from a steering wheel 33, and as an auxiliary means for laterally steering the vessel I have provided two horizontally disposed propellers 34—35 which are mounted upon horizontal shafts 36—37 disposed transversely of the vessel. These shafts, and the propellers carried thereby, are arranged to be driven by a suitable connection with the driving mechanism, the said connection in the present instance being a cross belt connection 38 with the longitudinal shaft 24. Clutches 39 and 40 are arranged for throwing the shafts 36 and 37 into, and out of, driving relation 80 with the driving mechanism at will, whereby one or the other of the propellers may be driven, or both of them may be released from driving connection. Normally it is intended that both of these propeller wheels 90 shall be out of driving relation, but that the one or the other shall be thrown into driving relation for steering purposes, the effect being, of course, to drive the rear end of the vessel around laterally whereby very 95 quick turns may be made when desired. Under ordinary circumstances it is impossible to steer an air ship except when the same is being propelled longitudinally, but with this form of steering mechanism it is 100 possible to turn the air ship while the same is otherwise stationary in the air. Thus, the air ship may, if desired, be turned around in substantially its own length instead of being compelled to take a wide sweep as is 105 common.

For power purposes I preferably provide two motors 41—42 each of which may comprise a multi-cylinder internal combustion engine, the fuel for which is carried in the compartments in the fore and aft extremity of the body, as has been above explained. These motors may be independently connected and disconnected with the drive shaft by means of individual clutches 43—44 115 whereby either or both may be employed for driving purposes, at will.

The motors and the propelling mechanism are all supported in a rigid framework 45 suspended from, and secured to, the body of the vessel as is shown, whereby the major portion of the weight of the vessel, as a whole, will be located below the center of the body of the vessel and stability therefore insured. The passenger car may be located 120 above the vessel body, as is shown at 46, the structure being as light in weight as is possible, the weight thereof when loaded with passengers being designed to be considerably less than the weight of the sub-structure 130

ture including the motors, the sub-frame, and the propelling mechanism.

The horizontal and vertical propelling elements may be of any suitable character, but preferably each element comprises a plurality of propelling blades disposed spirally around the shaft carrying them. The blades are conveniently arranged in pairs so as to balance their action, and the pairs are arranged some little distance apart upon spiral lines, as stated. Conveniently these propellers may be progressively shorter, and they may be surrounded by a conical casing 47, the object being to slightly compress the air as it passes to the successively arranged blades. This tends to compact the air and to give a better resistance to the propelling blades so as to add to their propulsive force. It is understood, of course, that there will be thereby caused a certain reaction upon the inclined surfaces of the conical chambers, but this reaction is more than offset by the advantages following from the greater resistance of the blades and to the expansive action of the air at the rear of the chambers, which add to the propulsive effect.

It will be noted that the vertically arranged propelling elements 19 are disposed beneath the body of the air ship, this being contrary to the general practice where vertically disposed propellers are employed, but this arrangement is advantageous and the lifting action thereof is not lessened, but rather increased, from the fact that while the propeller blades collect the air in front of them in all directions, they propel the air beneath them in substantially right lines. By this arrangement the vertical thrust is direct and practically uninterrupted.

For the purpose of taking advantage of the action of the wind when the same is blowing in the direction in which the vessel is pointing, I have provided sails 48 at the forward end of the vessel, the same being secured directly to the body of the vessel at one end and connected thereto by ropes 49 at the other. These sails will open out and

fill with wind when the vessel is going with the wind, but should the vessel be pointed toward or against the wind they will automatically close down to the side of the vessel and will offer practically no extra resistance thereto. Thus, the sails will be automatically set by the wind itself when they can give service, and will be equally automatically disposed of when they can be of no use.

What I claim is:

1. In an air ship, the combination with a buoyant body portion comprising a rigid framework, a shell whose cross-sectional contour is in the form of opposite symmetrical curves, the lateral extremities of which meet and form angles upon a horizontal medial plane, and a plurality of transverse vertical partitions which divide the interior of the shell into a plurality of chambers, of a motor supported by the framework beneath the shell, vertically and horizontally arranged propellers also supported by the framework beneath the shell, and a passenger car supported above the shell.

2. In an airship, the combination with a buoyant body portion comprising a rigid framework, a shell whose cross sectional contour is in the form of opposite symmetrical curves the lateral extremities of which meet and form angles upon a horizontal medial plane, and a plurality of transverse vertical partitions which divide the interior of the shell into a plurality of chambers, of a motor supported by the framework beneath the shell, vertically and horizontally arranged propellers also supported by the framework beneath the shell, horizontal rudders, horizontal pivots therefor which project laterally from the said body portion, upon opposite sides of the same, in the said medial plane of the shell, and a passenger car supported above the shell.

HERMANN SCHRÖDER.
